US00D689112S

(12) **United States Design Patent**
Henssler et al.

(10) **Patent No.:** **US D689,112 S**
(45) **Date of Patent:** **** Sep. 3, 2013**

(54) **VIDEO CENTRATION APPARATUS**

(71) Applicant: **Carl Zeiss Vision International GmbH**,
Aalen (DE)

(72) Inventors: **Heinrich Henssler**, Schwaebisch
Gmuend (DE); **Martin Schulteiss**,
Schwaebisch Gmuend (DE)

(73) Assignee: **Carl Zeiss Vision International GmbH**,
Aalen (DE)

(**) Term: **14 Years**

(21) Appl. No.: **29/445,490**

(22) Filed: **Feb. 12, 2013**

(57) **CLAIM**

The ornamental design for a video centration apparatus, as shown and described.

DESCRIPTION

FIG. 1 is a perspective view of an embodiment of a video centration apparatus of our new design;

FIG. 2 is a front elevation view of the video centration apparatus shown in FIG. 1;

FIG. 3 is a right side elevation view of the video centration apparatus shown in FIG. 1;

FIG. 4 is a rear elevation view of the video centration apparatus shown in FIG. 1;

FIG. 5 is a left side elevation view of the video centration apparatus shown in FIG. 1;

FIG. 6 is a top plan view of the video centration apparatus shown in FIG. 1; and,

FIG. 7 is a bottom plan view of the video centration apparatus shown in FIG. 1.

The broken lines illustrate portions of the video centration apparatus that form no part of the claimed design.

1 Claim, 7 Drawing Sheets
